UNITED STATES PATENT OFFICE.

WILLIAM HENRY PLEASANTS, OF VICTOR, COLORADO, ASSIGNOR OF ONE-HALF TO PERRY J. WEIPPER, OF SAME PLACE.

DESIGN FOR A MINER'S CANDLESTICK.

SPECIFICATION forming part of Design No. 30,991, dated June 13, 1899.

Application filed May 17, 1899. Serial No. 717,219. Term of patent 14 years.

To all whom it may concern:

Be it known that I, WILLIAM HENRY PLEASANTS, of Victor, in the county of Teller and State of Colorado, have invented and produced a new and original Design for a Miner's Candlestick, of which the following is a full, clear, and exact description.

Reference is to be had to the accompanying drawings, forming a part of this specification, in which similar characters of reference indicate corresponding parts in both views.

Figure 1 is a perspective view of a miner's candlestick, showing my design; and Fig. 2 is a transverse section of the same on the line 2 2 in Fig. 1.

The design in its entirety consists of a flat straight shank A, terminating at its outer end in a point B and at its inner end in a loop C, continuing into a flat straight bar D, bent upon the side of the inner end of the shank A, to then continue into a loop E of greater width than that of the flat shank A and ex-

tending below the same to abut with the upper portion E' of its end on the bar D and terminate in a reduced flat bar F, reaching transversely under the lower edge of the shank A, the end of said bar F being formed with a rounded-off shoulder F' and with an upwardly-extending tapering flat shank G', terminating in a hook G, extending transversely to the shank A.

The leading feature of the design consists of the flat shank A, the loop C, the bar D, and the abutting flat loop E of greater width than the shank A, and the transverse bar F, having the rising shank G' and the transverse hook G.

I claim—

The design for a miner's candlestick herein shown and described.

WILLIAM HENRY PLEASANTS.
